ATTORNEYS

UNITED STATES PATENT OFFICE.

AUSTIN F. TEIGEN, OF MOOREHEAD, MINNESOTA.

TOBACCO PIPE.

Application filed August 22, 1923. Serial No. 658,728.

To all whom it may concern:

Be it known that I, AUSTIN F. TEIGEN, a citizen of the United States, and resident of Moorehead, in the county of Clay and State 5 of Minnesota, have invented a new and useful Improvement in Tobacco Pipes, of which the following is a specification.

My invention relates to tobacco pipes and is particularly adapted to means for clarifying tobacco smoke before it is inhaled or drawn into the mouth of the smoker. It is understood that tobacco smoke contains surplus nicotine which, if not reduced, is very undesirable and poisonous to the smoker. 10 In my invention, I have developed simple effective means for readily clarifying the tobacco smoke and reducing the nicotine which is particularly adapted to a tobacco pipe of any nature.

20 The invention further includes means for cooling the tobacco smoke by virtue of the nature of my invention, wherein the tobacco smoke is drawn through a thin annular passageway extending around and longitudinal 25 of a solid core of suitable material so that the smoke, when received into the mouth of the smoker, is cool, mellow and refreshing rather than sharp and biting to the tongue which so often is the case with a tobacco 30 pipe so that the use of a tobacco pipe is much more limited than it would be where my invention is applied. The application of my invention to a tobacco pipe makes the same much more desirable to the smoker.

35 My attachment for a tobacco pipe is provided with means whereby it can be readily and quickly taken apart and cleaned thoroughly so that the pipe can be kept fresh and in condition to be used without having 40 any undesirable sourness or nicotine effect in smoking. It is a particular advantage of the invention to provide separable parts which can be removed from the pipe collectively or selectively when desired.

45 In the drawings forming part of this specification:

Figure 1 is a central cross sectional view of my pipe attachment as it would appear connected to an ordinary tobacco pipe.

50 Figure 2 is a section on the line 2—2 of Figure 1.

Figure 3 is a section of a portion of my device and the bowl of a pipe.

55 Figure 4 is a view of a portion of my device which is connected to the stem of the

pipe, a portion of which is illustrated in cross section.

The drawings illustrate an ordinary pipe bowl A, the stem neck 10 of which is curved from the bowl and which ordinarily supports the stem and mouthpiece of the pipe. 60

The portion 10 of the pipe A is formed with an opening 11 which is adapted to receive one end of my smoke clarifying unit B.

The smoke clarifying unit B is made up 65 of a hollow cylindrical portion 12 which is tapered off at 13 to fit into the opening 11, while the other end is provided with a ferrule 14 which is adapted to receive the stem or mouthpiece 15 of the pipe. The portion 70 12 of the unit B is adapted to receive a core member 16 which is formed of aluminum, or any other suitable material, and is provided on one end with an enlarged or flanged portion 17, while the other end is provided with 75 a similar flange or enlarged portion 18 positioned a short distance from the end of the same. At this end the core member 16 is threaded at 19 and is adapted to be threaded into the mouthpiece of stem 15 of the pipe. 80

The enlarged or flange like portions 17 and 18 are adapted to fit snugly within the tubular portion 12 so as to form an approximately air tight joint between the flanges 17 and 18 and the inner wall of the member 12. 85 In this manner, the core 16 positioned within the member 12 forms an annular longitudinally extending thin passageway or chamber 20. The ends of the core member 16 are provided with axially and transversely ex- 90 tendsing passageways 21 and 22 which connect the smoke passageway 23 leading from the bowl C of the pipe A with the passageway 24 in the stem 15, with the annular thin longitudinally extending passageway 20 95 interposed between the passageways 23 and 24 so that smoke passing from the bowl of the pipe A must pass through and be spread out in the thin annular passageway 20 before it can pass through the stem or mouth- 100 piece 15 to the smoker's mouth. In this manner, the smoke from the bowl C is brought into direct communication with the solid core 16 which, when made of metal such as aluminum or other suitable material, is 105 cooled sufficiently to condense the nicotine in the smoke and cause the same to lodge on the core and also within the lower end or pocket 25 formed by the lower portion of the annular passageway 20. The passageway 21 ex- 110

tends far enough into the core so as to provide a suitable space for the pocket 25 which is not interfered with by the draught of the smoke through the passageway 20 because 5 of the transversely-extending portion of the passageway 21 being positioned beyond the pocket space.

In the use of my invention, as applied and adapted to tobacco pipes, such as A or any 10 other suitable shape or form, it is readily apparent that the unit B can be attached in a suitable manner and is very desirable to provide a clean sweet smoke for a pipe. The unit B is composed of only the two 15 main parts 12 and 16 and the part, 16, being secured to the stem or mouthpiece 15, is readily removable as illustrated in Figure 4 so that it can be thoroughly cleaned, leaving the portion 12 empty so that it can also 20 be cleaned in a very effective manner. Thus it is apparent that the unit B is separable collectively from the pipe by detaching the same from the opening 11 or selectively by removing the core member 16. These features, together with the simple inexpensive 25 construction, provide a tobacco smoke clarifying means which is not only effective but desirable for any tobacco pipe. The solid portion of the core 16 provides sufficient body over which the thin annular passageway extends so as to cool and clarify the 30 tobacco smoke. This is an important feature of the invention.

In accordance with the patent statutes, I 35 have described the principles of operation of my invention together with the apparatus which I now consider to represent the

best embodiment thereof, but I desire to have it understood that the construction is only illustrative and that the invention can 40 be carried out by other means and applied to uses other than those above set forth within the scope of the following claims:

I claim:

1. A smoke clarifying unit having an 45 outer tubular member adapted to be interposed between the bowl and mouthpiece of a tobacco pipe, a separate core member removably held within said tubular member and having the end thereof adjacent said 50 bowl disposed entirely within said tubular member, means for spacing said core member from said tubular member in a manner to form a thin annular passageway about 55 said core member and said core member having passageways connecting said annular passageway with the bowl and mouthpiece of the pipe.

2. A three piece pipe consisting of a 60 bowl, stem and mouthpiece, said stem comprising a tubular member, a separate core member attached at one end to said mouthpiece and adapted to be removably positioned within said stem, the other end of 65 said core member being entirely enclosed within said stem, means for spacing said core member from said stem so that an annular passageway is formed between said stem and core and said core member having passageways connecting said annular passageway with the bowl and mouthpiece of 70 the pipe.

AUSTIN F. TEIGEN.
